US00D568308S

(12) United States Design Patent (10) Patent No.: US D568,308 S
Nakagawa (45) Date of Patent: * May 6, 2008

(54) PORTABLE COMPUTER

JP 01013936 * 7/1998
JP 1041331 6/1999

(75) Inventor: Hitoshi Nakagawa, Kadoma (JP)

(73) Assignee: Matsushita Electric Industrial Co., Ltd., Osaka (JP)

() Term: 14 Years

(21) Appl. No.: 29/267,714

(22) Filed: Oct. 18, 2006

(30) Foreign Application Priority Data

Apr. 20, 2006 (JP) 2006-010261

(51) LOC (8) Cl. 14-02

(52) U.S. Cl. D14/315

JP 981355 5/1997
JP 984167 7/1997

I claim the ornamental design for a portable computer, as shown and described.

CLAIM

DESCRIPTION

FIG. 1 is a top perspective view of a portable computer of the present invention seen in an open position;

FIG. 2 is a front view thereof;

FIG. 3 is a top view thereof;

FIG. 4 is a bottom view thereof;

FIG. 5 is a first side view thereof;

FIG. 6 is a second side view thereof;

FIG. 7 is a rear view thereof;

FIG. 8 is a top perspective view of the portable computer seen in a closed position;

FIG. 9 is a front view thereof;

FIG. 10 is a top view thereof;

FIG. 11 is a bottom view thereof;

FIG. 12 is a first side view thereof;

FIG. 13 is a second side view thereof; and,

FIG. 14 is a rear view thereof.
